UNITED STATES PATENT OFFICE.

MARQUETTE A. HEALY, OF CHICAGO, ILLINOIS, ASSIGNOR TO LYON & HEALY, OF CHICAGO, ILLINOIS, A CORPORATION OF ILLINOIS.

PIANO AND MUSIC RACK THEREFOR.

1,409,143.

Specification of Letters Patent.

Patented Mar. 7, 1922.

Application filed January 13, 1919. Serial No. 270,775.

To all whom it may concern:

Be it known that I, MARQUETTE A. HEALY, a citizen of the United States, residing at Chicago, in the county of Cook and State of Illinois, have invented a certain new and useful Improvement in Pianos and Music Racks Therefor, of which the following is a full, clear, concise, and exact description, reference being had to the accompanying drawings, forming a part of this specification.

My invention relates to pianos and particularly to music rests or racks for the same.

The principal object of the invention is to provide a piano having a music rack which will support the music when the cover of the piano is closed, but with the keys accessible, there being certain times when it is desired to play the piano in this condition.

A further object of the invention is to make it unnecessary to have more than one music rack, thereby saving expense and complication.

In accordance with my invention I provide the piano with a music rack or support which can be used in the piano when the cover is open and the piano in its usual playing position, and which can also be removed from the piano and placed in position upon the closed top of the same when said top is lowered into a closed position. Thus when the top is in that position and fall board open to expose the piano keys, the music rack may be used when playing notwithstanding the top is closed.

In the accompanying drawings Fig. 1 is a perspective view of a grand piano having a music rack or support embodying my present invention;

Fig. 2 is a plan view of the music rack or support by itself;

Fig. 3 is a cross section taken on line 3—3 in Fig. 2 on an enlarged scale.

Fig. 4 is a fragmental section on line 4—4 of Fig. 2.

Fig. 5 is a fragmental section of one of the sides of the piano.

Referring to the drawings, 1 is a grand piano having a top or cover 2 provided with a hinged front portion 3. This top or cover 2 may be swung or tilted about one edge so as to swing it into a more or less inclined open position, as desired for playing.

On top of the piano cover 2 I show a music rack or support 4. While this support may

be constructed variously, I have shown it provided with two end members 5—5, and two intermediate members 6—6 extended between and secured to the members 5—5, all the members 5—5 and 6—6 being preferably flat so that the support as a whole may rest readily upon the flat piano cover 2. A music supporting member 7 is hinged to the front member 6 so that it may be swung into an upright position, as shown in solid lines in Fig. 3, or into a horizontal position, as shown in dotted lines in said Fig. 3. Thus the member 7 may be swung into upright or horizontal position, as desired.

In order that the music rack 4 may not mar or scratch the piano cover 2, when placed upon the same, said rack 4 has its lower surface provided with suitable cushion supporting devices, such for example, as the rubber balls or lugs 8—8, Fig. 3. These are preferably secured to the under side of the members 6—6, as shown in dotted lines in Fig. 2. Thus the music rack or support may be safely put in position on the piano cover, when said cover is closed.

In Fig. 1, the fall board 10 of the piano is shown closed, but obviously said fall board may be tilted or swung back and up so as to expose the keys for playing, and this may be done, irrespective of the position of the cover 2. Thus when the cover 2 is down the fall board 10 may be in either open or closed position, being open when it is desired to play and still retain the cover 2 in a downward position. The piano rack or support 4 is preferably constructed so that it may not only be used for an outside music rack or support, as shown in Fig. 1, but may also be inserted into the piano in order that it may be used for a music support when the piano cover 2 is open.

To such end the ends of the members 5—5 are grooved as at 11, and the sides of the piano case are provided with rails or shoulders 12 adapted to fit in the grooves 11, whereby the rack or support 4 may be slid back and forth in the piano and also into and out of the piano case. When the cover is to be elevated and the piano played in such condition, the member 4 is removed from the position on top of the cover as shown in Fig. 1, and is slid into the piano case so as to be in position within the same to permit playing with the cover open.

Thus a single piano rack will serve for the

double purpose of an outside rack for use with the piano cover closed, and also as an inside rack to be used with the piano cover open.

5 It will be understood that changes and modifications may be made without departing from the spirit of the invention.

What I claim is:

1. A piano having a portable music rack, 10 said piano and rack being provided with means for supporting the rack slidably in the piano, said means permitting the rack to be bodily withdrawn from the piano, and said rack being provided with cushioned feet 15 adapted to rest on the top of the piano case.

2. A grand piano and a portable music rack therein, said piano and rack being provided with means for supporting the rack so that the same may be slid horizontally in 20 the piano, said means permitting the rack to be slid bodily out of the piano and said rack having its under side provided with cushioned projections.

3. A piano having keys and a front hinged 25 cover section, rails on the inner surfaces of the sides of the piano beneath said cover sec-

tion, a music rack having end portions provided with marginal grooves forming shoulders to rest upon said rails, and rubber feet on said end portions, said rack being removable from said rails and adapted to rest upon 30 said cover when the same is closed.

4. A grand piano having straight side walls at its front and rails on the inner surfaces of said walls, a hinged front cover 35 section adapted to close down and conceal said rails, a music rack comprising parallel members lying transversely of the piano and having connecting end portions, grooves in the under outer margins of said portions 40 forming shoulders adapted to rest upon said rails and permit sliding movement of the rack, said portions having feet on their under surfaces, and said rack being removable from said rails and adapted to rest upon 45 said feet on said cover section when the latter is closed.

In witness whereof, I hereunto subscribe my name this 21st day of December, A. D., 1918.

MARQUETTE A. HEALY.
